MARKING GAUGE

Michael E. Nowak, Cleveland, Ohio

Application April 3, 1948, Serial No. 145,510

Term of patent 14 years

(Cl. D52—1)

To all whom it may concern:

Be it known that I, Michael E. Nowak, a citizen of the United States and a resident of Cleveland, in the county of Cuyahoga and State of Ohio, have invented a new, original, and ornamental Design for a Marking Gauge, of which the following is a specification, reference being had to the accompanying drawing, forming a part thereof, in which

Fig. 1 is a top plan view of a marking gauge showing my new design; and

Fig. 2 is an edge view of the marking gauge.

I claim:

The ornamental design for a marking gauge, substantially as shown.

MICHAEL E. NOWAK.
